UNITED STATES PATENT OFFICE

ALEXANDER M. KNAUBER, OF CHICAGO, ILLINOIS

LIGHT-COLORING SCREEN

Application filed November 7, 1927, Serial No. 231,406. Renewed September 23, 1929.

The invention relates to improvements in light-coloring means, generally known as a color screen, by the use of which light rays are given characteristic colors by passing them 5 therethrough.

The present invention relates especially to so-called light-coloring screens that are used in connection with electric lamps in theatres, dance halls and the like, for coloring the flood 10 lights that are projected upon or about the stage of a theatre or on suitable surfaces in other assembly halls.

The color screen as herein disclosed is especially adaptable for use in front of lamps 15 for border lights, proscenium lights, cyclorama lights and the like for illuminating the stage of a theatre, altho the device has many and varied uses as will be apparent to one skilled in the art.

Heretofore perishable substances of a gelatinous nature have been used to give color 20 to the light rays for this purpose. Celluloid, tamidine and the like have proven to be unsatisfactory. Gelatine is short lived. It very soon crissels and becomes brittle and breaks 25 up as a result of the intense heat from the lamps to which it is subjected. Celluloid is explosive or combustible. Glass as used heretofore has not been practicable because the 30 localization of heat in large plates of glass sets up such intense internal stress that very often causes the glass to explode with violence and scatter its pieces around and about to the great danger of persons near by.

One of the objects of the invention is to 35 make a durable screen of high efficiency.

Another object is to make a screen plate in 40 separable plate sections leaving room for each section plate to expand freely in all directions.

A further object is to provide a frame from 45 which the smaller plate sections are freely removable and readily replaced.

A still further object is to provide a composite plate which may contain many section 50 plates, of various colors, whereby the field of light will be a composite of all of the blended colors to produce many and various chromatic effects.

Another object is to provide a metal frame

in which glass plates may be used with no resulting danger of injury to the plates or objects in the vicinity.

It is a further object of the present invention to provide a color screen of the character 55 described which may be efficiently and expeditiously taken down and reassembled in different order to produce desired composite, blended, or chromatic effects.

Other objects, advantages and benefits will 60 readily appear to persons skilled in the art from a consideration of the following description and of the drawings forming a part hereof, wherein:

Figure 1 is a side elevation, with parts in 65 section, of a device embodying principles of the present invention.

Figure 2 is a transverse section taken substantially along line II—II of Figure 1.

Figure 3 is a fragmentary section taken 70 substantially along line III—III of Figure 1.

Figure 4 is a fragmentary elevational view of the upper part of Figure 1.

Figure 5 shows the device equipped with 75 substantially transparent or translucent means of different colors.

In all the views the same reference characters are used to indicate similar parts.

The structure arbitrarily selected to illustrate an embodiment of the invention includes 80 a substantially rectangular frame 10 preferably made of metal, such as sheet metal, copper being highly desirable since it is a good conductor of heat, the temperature being thereby equalized to a better degree throughout the screen.

When the screen is in use, it is customarily 85 placed in front of a floodlight box containing powerful electric lamps from which the light is concentrated to some extent upon a zone near the central area of the screen. Plates or panes 11, preferably of glass fit loosely in the respective sections of the frame so that they each may expand in all directions without affecting any other plate and without stressing the frame.

The heat from electric lamps reaches its 90 maximum effect very quickly and when it is concentrated upon the central zone of a screen 95 of the type comonly known heretofore, the 100

metal and glass cannot disseminate the excessive heat with sufficient celerity to avoid the disastrous results effected by sudden expansion of the highly heated area.

6 This is especially true if the screen consists of a single large plate of glass, or when a plurality of smaller plates are placed in a tight fitting frame. This result is exaggerated when the metal of the frame is a relatively poor 10 conductor of heat. When the metal of the frame is not a good conductor of heat, the inside surface (that next to the lamps) will expand more rapidly than the outside surfaces thereof, thus warping or buckling the 15 frame and breaking the plates. To overcome these objections, the colored plates 11 are preferably made rather thin, and mounted loosely in their respective sections of the frame.

20 Another refinement or advantage presented in my structure consists of the facility with which the small plates of glass may be inserted and removed from the frame for repair or to make up a polychromatic screen.

25 The outside members of the rectangular frame consist of three channel bar members 12, 13 and 14, leaving the upper end, as shown in Figures 1 and 4, of the drawings, without a channel bar. These channel bars are preferably made of sheet copper. They are metered at the corner 15. The bars 12 and 14 extend vertically from the bar 13 when the screen is in use. There are two parallel intermediate bars 16 and 17. The bars 12-17 30 are equal in width and they are all channel bars, but bars 16 and 17 are provided with double channels, as shown in Figure 3, while the bars 12-14 have only one channel. The upper ends of all of the vertical bars are connected together by an angle strip 18. When flat plates 11 only are used, the strip 20, as shown in Figures 1 and 2, may also be used.

When the plates have lateral protuberances like "bulls eyes", the strip 20 may be omitted, 45 as shown in Figure 4.

The plates 11 are freely slidable between adjacent vertical bars and may be readily removed and replaced. Separating transversely positioned channel bars 21 overlie the upper edges of the plates 11. The ends of the channel bars 21 lie within the channels of the vertical bars and are freely slidable therein.

The sides of the margin of the plates 11, therefore, do not ordinarily touch the ribs 55 forming the channels of the vertical bars. The cross bars 21 move in all directions with the plate and in that way the plate is protected against injury due to warping of the frame.

60 A closure strip 22 is slidable over the strips 18 and 20 and closes the openings through which the plates pass into the respective sections of the frame. The closure strip also adds strength to the upper edge of the frame.

65 As seen in Figure 2, the uppermost panes are

spaced considerably below the closure member 22, so that the panes may expand upwardly by simply forcing superposed panes and short bars 21 thereabove.

To remove plates 11 and bars 21, the cover 70 22 is slipped off and the plates and cross bars are moved vertically from between the vertical bars. When glass plates of differing colors are placed in the frame, as shown in Figure 5, the field of illumination is a blended 75 composite color.

It will be observed that the plates 11 do not ordinarily make contact with the vertical bars 12 to 14 inclusive, nor with any one of them, and consequently the plates 11 are substantially unaffected by bending of the vertical bars to the extent to which the terminals therof are displaced in actual use.

80 From the foregoing, it will be apparent that I have provided a color screen of the character described herein which utilizes a plurality of individual and removable panes incorporated in a frame in such a manner that the panes may freely expand in any direction. Moreover, various polychromatic 85 and blended effects are obtainable with the present invention by properly adjusting the same, and due to its peculiar construction the device is extremely durable, exceedingly simple in operation, and may be economically 90 manufactured.

95 I am aware that many changes may be made, and numerous details of construction 100 may be varied through a wide range without departing from the principles of this invention, and I therefore do not purpose limiting the patent granted hereon, otherwise than necessitated by the prior art.

I claim as my invention:

1. A light-coloring screen comprising a 105 frame having a plurality of parallel, fixed and spaced channel bars to receive a plurality of glass plates therebetween; glass plates between adjacent bars and freely slidable therein; and transverse channel bars between the fixed bars and separating the adjacent glass plates, the transverse bars and the plates being removable.

110 2. A screen, as characterized by claim 1, in which the transverse channel bars are entirely within the transverse outlines of the fixed bars.

115 3. A screen, as characterized by claim 1, in which the transverse bars and the plates therebetween are freely slidable between adjacent fixed bars.

120 4. A light-coloring screen having a frame comprising parallel fixed and spaced channel bars, a plurality of rectangular glass plates between adjacent fixed bars and transverse channel bars separating said adjacent plates, said plates and said transverse bars being loose and free to expand without warping the screen.

125 5. A light-coloring screen comprising a rec-

tangular frame having a plurality of spaced, fixed parallel bars, a plurality of loose transverse bars between adjacent fixed bars and a plurality of glass plates between adjacent fixed bars separated by the transverse bars, said plates and transverse bars being loosely supported in said frame.

5 6. A screen, as characterized by claim 1, in which the panes or plates make contact only with said transverse, slideable channel bars.

10 7. In a device of the character described, a plurality of spaced and fixed channeled members, panes slideable in the channels of said members, and other channeled members slideable in said channels between said panes.

15 8. In a device of the character described, a pair of fixed members, panes insertable between said members, and members for separating said panes insertable transversely between said fixed members.

20 9. In a device of the character described, a plurality of fixed frame members, panes slideable between adjacent frame members, and means for separating adjacent edges of said panes.

25 10. In a device of the character described, a plurality of fixed bars, a plurality of panes loosely mounted between said bars, and a plurality of transverse bars loosely mounted between adjacent edges of said panes.

30 11. In a device of the character described, a frame, and a plurality of individual panes mounted therein in such a manner that said panes may freely expand in any direction.

35 12. In a device of the character described, an open sided frame, a plurality of channel bars in said frame, a plurality of panes loosely slideable between adjacent channel bars, channel bars transversely slideable between adjacent said first mentioned bars for separating the panes, and a removable closure for the open side of said frame.

40 13. In a device of the character described, a plurality of frame members, panes mountable between adjacent frame members, and means to separate adjacent edges of said panes, said panes and said means being free to move in all directions.

45 In testimony whereof I have hereunto subscribed my name at Chicago, Cook County, Illinois.

ALEX. M. KNAUBER.
